UNITED STATES PATENT OFFICE

129,741

DESIGN FOR AN ICE-CREAM CONE TRAY OR SIMILAR ARTICLE

Frederick E. Clark and Willie D. Marshall, Ringgold, Va.; said Marshall assignor to T. H. Gough, Ringgold, Va.

Application July 7, 1941, Serial No. 101,928

Term of patent 3½ years

To all whom it may concern:

Be it known that we, Frederick E. Clark and Willie D. Marshall, citizens of the United States, residing at Ringgold, in the county of Pennsylvania and State of Virginia, have invented a new, original, and ornamental Design for an Ice-Cream Cone Tray or Similar Article, of which the following is a specification, reference being had to the accompanying drawing, forming part thereof.

cone tray or similar article, showing our new design.

We claim:

The ornamental design for an ice-cream cone tray or similar article, as shown.

FREDERICK E. CLARK.
WILLIE D. MARSHALL.
